(57) **CLAIM**

The ornamental design for a vacuum cleaner roller, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a perspective view of a vacuum cleaner roller, illustrating our new design;
FIG. 2 is a first side view thereof;
FIG. 3 is a second side view thereof;
FIG. 4 is a right side view thereof, shown in enlarged scale;
FIG. 5 is a left side view thereof, shown in enlarged scale;
FIG. 6 is a third side view thereof; and,
FIG. 7 is a fourth side view thereof.

1 Claim, 7 Drawing Sheets
